UNITED STATES PATENT OFFICE.

EDWIN C. HYLAND, OF MILWAUKEE, WISCONSIN.

TROUSERS-HANGER.

SPECIFICATION forming part of Letters Patent No. 739,260, dated September 15, 1903.

Application filed January 24, 1903. Serial No. 140,385. (No model.)

To all whom it may concern:

Be it known that I, EDWIN C. HYLAND, a citizen of the United States, and a resident of Milwaukee, in the county of Milwaukee and State of Wisconsin, have invented certain new and useful Improvements in Trouzers-Hangers; and I do hereby declare that the following is a full, clear, and exact description thereof.

10 My invention relates to devices for suspending trousers when not in use; and it consists in certain peculiarities of construction and combination of parts, as will be fully set forth hereinafter in connection with the accompanying drawings and subsequently claimed.

15 In the said drawings, Figure 1 is a view in front elevation of my said device, partly broken away to better illustrate certain details of construction. Fig. 2 is a vertical central sectional view of the same with the upper hanger in a changed position.

20 Referring by numerals to the drawings, 1 and 2 represent the standards of the device, united by the top piece 3 and the lower brace 4. Journaled in the standards are the hangers, four of which are shown (marked, respectively, 5, 6, 7, and 8) and whose side arms regularly increase in length, as shown, the arms of the upper hanger 5 being the shortest and those of the lower hanger 8 the longest of all. On a line vertically forward of the vertical line of the pivotal points of the hanger-arms one of the standards is provided with a series of horizontal perforations fitted 25 with spring-bolts 9 for supporting the hangers in horizontal position, as shown with hanger 5 in Fig. 2.

25 My device is adapted to be either suspended, as from the screw-eyes 10, on nails, screws, or other projections upon a wall or closet or wardrobe door or to stand upon the base 11, as preferred in any instance, and if economy of space is necessary when the device is suspended, as from the inner side of a door, the base 11 can be readily removed, as it is held to the standards 12 by the frictional contact of the dowel-pins 12 within corresponding bores in the lower ends of the standards, although the said base 11 makes a very convenient shoe-shelf in use.

30 The operation of my device will be readily understood from the foregoing description of its construction, taken in connection with the

accompanying drawings. When it is desired to suspend the trousers upon the hangers, 55 the spring-bolts are withdrawn and the hangers raised to the horizontal position and the bolts allowed to spring back, so that the hangers will be supported thereby, as illustrated with the upper hanger 5 in Fig. 2, and the 60 trousers are doubled and suspended upon the hangers, which swing back to their normal position when the spring-bolts are again retracted, and as each successive hanger projects forwardly to a point beyond that of the 65 projection of the hanger above there is no interference between the trousers on the different hangers even when all the said hangers are projected at the same time.

70 My device will be found extremely convenient, particularly where economy of space is desired, and owing to its extreme simplicity there is practically nothing about it to get out of order at any time, and as the hangers are all of a double-crank shape the arms lie close 75 to the standard when in their normal or suspended position, whereby practically the entire space between the standards is utilized.

Having thus described my invention, what I claim as new, and desire to secure by Letters 80 Patent, is—

1. In a trousers-hanger, the combination with a pair of upright standards, of a top piece and lower brace uniting said standards, a series of hangers, each of a double-crank shape, journaled at their ends to said standards, and having free movement between them, and a series of spring-bolts for engagement with the hanger-arms. 85

2. In a trousers-hanger, the combination with a pair of upright standards united by a top piece and lower brace, of a series of double-crank-shaped swinging hangers suspended from the upper ends of their arms to and between said standards, and each succeeding 95 hanger having arms of greater length than the one above, and a series of spring-bolts for engagement with the hanger-arms. 90

In testimony that I claim the foregoing I have hereunto set my hand, at Milwaukee, in 100 the county of Milwaukee and State of Wisconsin, in the presence of two witnesses.

EDWIN C. HYLAND.
